UNITED STATES PATENT OFFICE.

NORMAN T. HARRINGTON, OF CLEVELAND, OHIO.

LOADING AND UNLOADING APPARATUS.

Application filed May 6, 1920. Serial No. 379,377.

To all whom it may concern:

Be it known that I, NORMAN T. HARRINGTON, a citizen of the United States, residing at Cleveland, in the county of Cuyahoga and State of Ohio, have invented a certain new and useful Improvement in Loading and Unloading Apparatus, of which the following is a full, clear, and exact description, reference being had to the accompanying drawings.

This invention relates to systems for handling loads, and more particularly to a system embodying two towers supporting a cable-way for a load-handling device and capable of being rocked simultaneously about their respective pivots in order to enable the load-handling device to operate upon material covering a wide area. A system of this type is disclosed in my application No. 354,123 filed January 26, 1920. It is the general purpose and object of this invention to operate the towers in a particularly efficient manner; also to render the system safe in operation and especially in the event of the breaking of the cable by which the auxiliary or "tail" tower is operated from the main or "hoist" tower. Further and more limited objects of the invention will appear hereinafter and will be realized in and through the combinations of elements embodied in the claims hereto annexed.

In the drawings forming part hereof, Fig. 1 represents an elevation of a load-handling system embodying my invention; Fig. 2 an elevation of one of the towers shown in Fig. 1, the view corresponding substantially to the line 2—2 of Fig. 1; Fig. 3 an elevation of one of the towers taken from the opposite side of the same from Fig. 2; Fig. 4 is a detail in elevation of the lower part of the main or hoist tower; Fig. 5 is a sectional detail of said tower corresponding substantially to the line 5—5 of Fig. 4; Fig. 6 a detail in elevation and Fig. 7 a detail in plan of the upper portion of such tower; Fig. 8 is a detail in elevation of the base of the auxiliary or tail tower; Figs. 9 and 10 are details in elevation and in plan, respectively, of the upper end of the last mentioned tower; Fig. 11 a detail in perspective; Fig. 12 a detail in elevation of the brake mechanism for the tower rocking drums; and Fig. 13 is an enlarged view of a detail.

Describing the parts by reference char-

acters, 1 denotes the main tower and 1^a the auxiliary tower, the two towers being substantially identical in construction. The towers are angularly movable about a horizontal axis and are provided with mechanism for tilting them in unison.

While there is, of course, considerable latitude in the selection of mechanical detail for operating the towers as a single mechanical unit, the drawings represent what I have found to be a particularly advantageous arrangement which I consider as the preferred form.

The towers terminate at the bottom in bearing lugs 68^a. While the lugs 68^a of tower 1 have journals 68^b revolvably supported in bearings 68, the lugs 68^a of tower 1^a are mounted upon a shaft 2^a.

The means for tilting the towers include a pinion 16 in mesh with a segmental rack 17. Power is transmitted to the pinion 16 on tower 1 from a motor 3 through gears 4 and 5 to a shaft 2 extending through the journals 68^b, then from shaft 2 through beveled gears 6 and 7, shaft 8, bevel gears 9 and 10 to a shaft 12 and from shaft 12 through bevel gears 13 and 14 to shaft 15 carrying the pinion 16.

The shaft 12 which has been interposed between shaft 15 and shaft 2 to provide means for conveniently translating the motion of the motor 3 to tower 1^a to tilt it in unison with tower 1 carries a drum 11 about which are wrapped in opposite directions cables 18 and 18^a. The cables extend from drum 11 over sheaves 19 at the top of tower 1 and sheaves 19 at the top of tower 1^a to a drum 11 mounted upon a shaft 12. The shaft 12 in turn is connected through gears 13 and 14 to a shaft 15 which carries a pinion 16 in mesh with a rack 17, the arrangement being the same as on tower 1.

When the motor 3 is operated, the two towers will thus be tilted in unison in one direction or the other according to the direction of rotation of the motor which is subject to control.

Each of the towers is shown as provided with a counter weight 20 mounted in vertical guideways 21 and connected each to its tower at a point above the center of gravity thereof and of its load, preferably near the top of such tower (see Figs. 1 and 2). For the purpose of connecting each counter weight to its tower, I employ a cable 22 which is connected at its lower end to the

counterweight and is pivoted at its upper end upon a pintle 23 projecting from such tower. The vertical guideways are shown as provided with guys 24 connected to opposite ends of horizontal frame members 25 at the top of the said guideways. The frame members 25 are provided with bearings 26 to which are pivoted sheave segments 27. Each sheave segment is provided with a track for the cable 22 as well as with a track or groove for a cable 28, the upper end of each cable 28 being connected to its sheave segment and the lower end thereof extending beneath the opposite sheave segment and being secured to a projection 29 thereon. By this manner of connecting the sheave segments, the rocking of either of such segments by the cable 22 will cause the other sheave segment to rock in unison therewith. One of the towers is shown in full lines in Fig. 2 at one extreme of its rocking movement and in dotted lines in the other extreme position as well as in a vertical position. The construction and arrangement of the parts 20—29 inclusive is described, illustrated and claimed in my application No. 354,123, referred to hereinbefore.

30 denotes a cable-way which is connected at one end to the tower 1, as indicated at 31, and at its other end to the tower 1^a, as by means of a tackle having its movable block 32 connected to the said cable-way and its fixed block 33 connected to the upper end of the tower 1^a.

Mounted upon the cable-way is a carriage 34 supporting a bucket 35. This bucket will be provided with the usual hoist, opening, closing and travel lines, the towers being provided with sheaves 36 and 37 for such lines, and one of the lines being indicated at 38. These lines will be operated in any convenient manner, and illustration of the same and of the operating means will be unnecessary for an understanding of the invention disclosed herein. As in the case of the system shown in my prior application, each tower is provided with a guy 39 which is connected thereto at its upper end, the lower end of each guy being connected to a horizontal pivot 40 which is in line with the tower pivots, whereby the effective lengths of the guys are not altered by reason of the rocking of the towers.

In order to render the towers safe in operation, preventing the falling of the tail tower through the parting of either rocking cable as well as the falling of either tower through over balancing, the following construction is provided:

The sheaves 19 are mounted in frames or brackets 41. Each of these frames or brackets is mounted on a vertically extending stud or peg 42 (see Figs. 6, 7, 9 and 10). The upper end of each peg or stud is normally held

by the tension of its cable 18 within a slot 43 provided within a horn or projection 44 secured to the upper end of the tower. The lower end of each peg or stud is mounted upon a shaft 45 which is supported by its tower. 46 denotes a pair of rods, located on opposite sides of the top of each tower and each pivoted at its inner end to an arm 47 of a bell crank lever having its shaft 47^a pivoted to the tower at 48. Each rod 46 is provided with an eye 49 through which its cooperating pin or stud 42 extends. Mounted on the outer end of each rod 46 is an abutment 50 between which and the adjacent face of the tower a helical spring 51 is interposed. These springs tend to pull the rods 46 outwardly but, their initial strain or compression being less than the strain normally exerted upon and by their respective cables 18, they are ineffective to rock the pins or studs and their respective bell crank levers. The arm 52 of each bell crank lever is connected preferably through a downwardly extending link 53^a to one end of a lever 53 which is pivotally supported between its ends as by an eye in a strap 54. The other ends of the levers 53 have slots 53^b through which extends a bolt 55 whereby the levers 53 may have an overlapping sliding motion relatively to each other. With this arrangement of parts, the rocking of either bell crank lever by its spring 51 will result in the rocking of the lever 53 connected thereto. The arrangement of levers and the straps 54 is such that a rise of the inner end of the lever 53 in the manner referred to merely lifts the bolt 55 and the other lever 53 without affecting the bell crank lever connected to the latter.

Extending downwardly from the connected ends of the lever arms 53 and connected to the bolt 55 is a rod 56. The lower end of this rod (see Figs. 4 and 8) is provided with an elongated eye 57 by means of which it is connected to one arm 58 of an angle lever, the opposite arm 59 of which is provided with a hook or latch 60 adapted to engage the end of one arm 61 of a lever, pivoted at 62. The opposite arm 63 of the last mentioned lever is subjected to the compression of a spring 64 mounted on a bolt 64^a to depress the arm 63 and lift the arm 61. The extreme inner end of the lever arm 58 is connected to a rod 65 which is provided at its lower end with a roller 66 adapted to operate upon one of the cylindrical bearing hubs 68 in which the pivots 2 and 2^a are journaled. In order to maintain the rod 65 in a vertical position, a link 65^a is connected to the same and to one of the side faces of the tower-supporting bracket 1^b. On each side of the hub 68 is a shoe 69 which, when either tower is rocked to a predetermined extent, will be engaged by its roller 66, thereby to rock the angle or bell crank lever 130

to which the rod 65 is connected and disengage the hook or latch from the lever arm 61. The spring 64 will then rock the lever 61, 63 and, through connections to be described, apply a brake, indicated at 70, to its drum 11^a.

The lever 58-59 will also be operated to release the lever 61, 63 should either of the cables 18 break. When this happens, the tension of the appropriate spring 51 will be sufficient to move its peg 42 rearwardly, thereby rocking the appropriate bell crank lever arm 52 and, through the upward movement of the inner end of the lever arm 53, pull upwardly upon the rod 56, thereby tripping the lever 58, 59 and enabling the spring 64 to apply the brake to the drum.

Each tower will be provided with the safety mechanism hereinbefore described, and the parts of the tail tower corresponding to those of the hoist tower will be designated by like reference numerals. The manner in which the brake band is applied to the rocking drum of each tower will now be described.

71 denotes a brake rod having an eye 72 by means of which a connection between the rod and the lever arm 63 is secured, as by means of a pin 73 carried by said arm and extending through said eye. Each brake rod is connected at its upper end to a pair of plates 74, 75, as by means of a pin 76^a. Each plate is provided at the end opposite the said connection with an upward extension 74^a, 75^a, respectively, each provided with a journal 76, 77, for a stud 78 the outer ends of which are mounted in slots 80 in a pair of plates 79. Between the journals 76, and 77 the stud is provided with a spacing sleeve 78^a. 81 denotes a bolt extending through the plates 74 and 75 beneath the journals 76 and 77 and supporting a block 82 through which extends a bolt 83 having its other end journaled upon a stud 84 and mounted in slots 80^a in the opposite ends of the plates 79 from the slots 80. One end of a brake band 70 is connected to the stud 78 by means of journals 86 and the opposite end of said band is connected to the stud 84 by similar journals 86^a. The plate 75 is provided with a downwardly extending projection 75^b to which a spring 86^b is connected, the opposite end of said spring being connected to a rigid member 87 of the tower, as by means of an eye bolt 88. The end of the brake band which is connected to the stud 84 is provided with an abutment 89 adapted to be engaged by the end of a screw 90 which extends through a block 91 journaled in a pair of frame members 92 beneath said band, as indicated at 93. The plates 79 are anchored to member 92 and 92^a secured to the tower, as by rivets 79^a.

By the construction described, when one of the rocking cables breaks, the springs 51

on the two towers corresponding to such cable operate through the rod 56 to disengage the hook 60 from the lever 61, 63. Thereupon the springs 64 in the two towers depress each an arm 63, pulling down upon the rod 71 and, through the connections 74-93, applying the brakes 70 to the drums 11^a. The brake mechanism described constitutes a double-acting brake which is capable of operating promptly and efficiently upon each drum irrespective of the direction in which it may be rotated and a brake band may be employed which is practically coextensive with the exterior of the drum with which it cooperates and which will engage such surface throughout its full length. Furthermore, should the towers be rocked further than desirable in either direction, the rollers 66 and rod 65 will unlatch the hook 60 from the lever 61 and the brakes will also be applied to the tower drums 11^a.

It is desirable that, when the brakes are applied, the action of the motor on the drum should be suspended. This is conveniently accomplished by extending the lever arm 63 to form one member 63^a of a knife-blade switch, the other member of which is indicated at 94. These switch members are in the circuit of the motor 3 and are provided with conductors 95 and 96 leading to said motor, so that, when the switch members 62^a and 94 are separated by the appropriate spring 64 in the hoist tower, the motor circuit will be opened, and the rotation of the shaft 2 will be discontinued, automatically suspending the rocking of the hoist tower by the gears 13, 14, 16 and the gear segment 17.

In addition to the automatic means for applying the brake to the drum of the hoist tower, I provide means for applying the said brake by hand. For this purpose, the eye 72 in the rod 71 is elongated and the rod is extended below the lever arm 63 and provided with an elongated eye 72^a. This eye receives a pin 97 carried by one arm 98 of an angle lever, pivoted at 99, the other arm 100 being provided with a yoke 101 by means of which it is connected to a sleeve 102 loosely mounted on the shaft 2 and provided with pins 103 adapted to receive the fork of a hand operating lever (not shown). By this construction the brake may be applied by hand to the drum of the hoist tower without affecting the lever 61, 62.

Having thus described my invention, what I claim is:

1. The combination, with a pair of angularly moving towers, a cableway extending between and supported by said towers and a load handling device on said cableway, of means including a drum for rocking one of said towers, a drum in the other tower, cables connecting said drums, a shaft,

- means for driving the same, connections between said shaft and the drum of the first mentioned tower, a brake for each drum, means operated by the rocking of each tower 5 for applying the brake to its drum when such tower shall have been rocked to a predetermined extent from a vertical position, means operative by the breaking of either of said cables for applying said brakes to 10 said drums, and means operated by the rocking of the towers and by the breaking of either of said cables for making the driving connections between said shaft and the first mentioned drum inoperative.
- 15 2. The combination, with a pair of angularly moving towers, a cableway extending between and supported by said towers and a load handling device on said cableway, of means for rocking one of said towers, connections for rocking the other tower from the first mentioned tower, a brake for the rocking means of each tower, means operated by the rocking of each tower for applying the brake to its rocking means 20 when such tower shall have been rocked to a predetermined extent from a vertical position, means operated by the breaking of such rocking connections for applying the said brakes, and means operated by the 25 rocking of the towers and by the breaking of such rocking connections for suspending the operation of the means for rocking the first mentioned tower.
3. The combination, with a pair of angularly moving towers, a cableway extending between and supported by said towers and a load handling device on said cableway, of means including a drum for angularly moving one of the said towers, a drum 35 for the other tower, a brake for each of said drums, cables leading from the drum on the first tower to the drum on the second tower and normally held in one position by the pressure exerted by the cable, movably supported sheaves for the said cables carried by each tower, means tending to move said sheaves against said pressure, a rod connected to the brake for each tower, a lever to which each rod is connected, means tending to move each lever in a direction to apply the brake with which its rod is connected, a latch for retaining each lever against operation, and connections between each sheave and the latch of each tower for releasing the said latch through the movement of the sheave.
4. The combination, with a pair of angularly moving towers, a cableway extending between and supported by said towers and a load handling device on said cableway, of means including a drum for angularly moving one of the said towers, a drum for the other tower, a brake on each of said drums, cables leading from the drum on the first tower to the drum on the second tower, 60 movably supported sheaves for the said cables carried by each tower, means for connecting each lever to the brake for its tower, means tending to move each lever in a direction to apply its brake, a latch for retaining each lever against operation, means for rotating the drum of the first tower, and means operative by the rocking of each tower for automatically suspending the drum of the first tower.
5. The combination, with a pair of angularly moving towers, a cableway extending between and supported by said towers and a load handling device on said cableway, of means including a drum for angularly moving one of the said towers, a drum for the other tower, a brake for each of said drums, cables leading from the drum on the first tower to the drum on the second tower, 65 movably supported sheaves for the said cables carried by each tower, normally inoperative means tending to move said sheaves, a rod connected to the brake for each tower, a lever to which each rod is connected, means tending to move each lever in a direction to apply the brake with which its rod is connected, a latch for retaining each lever against operation, a shaft for rotating the drum of the first tower, and means operative by the brake rod in said tower for breaking the driving connections between said shaft and said drum.
6. The combination, with a pair of angularly moving towers, a cableway extending between and supported by said towers and a load handling device on said cableway, of means including a drum for angularly moving one of the said towers, a drum for the other tower, a brake on each of said drums, cables leading from the drum on the first tower to the drum on the second tower, 70 movably supported sheaves for the said cables carried by each tower, normally inoperative means tending to move said sheaves, a lever supported by each tower, means connecting each lever to the brake for its tower, means tending to move each lever in a direction to apply its brake, a latch for retaining each lever against operation, means for rotating the drum of the first tower, and means operative by the lever in said tower for suspending the operation of the drum rotating means.
7. The combination, with a pair of angularly moving towers, a cableway extending between and supported by said towers and a load handling device on said cableway, of means for rocking one of said towers, connections for rocking the other tower from the first mentioned tower, brake mechanism carried by each tower for limiting the rocking movement thereof, means operative by the rocking of each tower for applying the brake mechanism thereto, and means operated by the rocking of the first mentioned tower for automatically suspending the drum of the first tower.

ing the operation of its rocking means when said tower has been rocked a predetermined distance from the vertical.

8. The combination, with a pair of angularly moving towers, of a cableway extending between and supported by said towers and a load handling device on said cableway, of means for rocking one of said towers, connections for rocking the other tower from the first mentioned tower, brake mechanism carried by each tower for limiting the rocking movement thereof, and means operative by the rocking of each tower for applying the brake mechanism thereof.

9. The combination, with a pair of angularly moving towers, a cableway extending between and supported by said towers and a load handling device on said cableway, of means including a drum for rocking one of said towers, a drum in the other tower, cables connecting said drums, means for driving the drum in the first mentioned tower, a brake for each drum, means operated by the rocking of said towers for applying said brakes when the said towers have been rocked to a predetermined extent from a vertical position, and means operated by the breaking of either of said cables for applying said brakes to said drum.

10. The combination, with a pair of angularly moving towers, a cableway extending between and supported by said towers and a load handling device on said cableway, of means including a drum for rocking one of said towers, a drum in the other tower, cables connecting said drum, means for driving the drum in the first mentioned tower, a brake for each drum, and means operated by the breaking of either of said cables for applying said brakes to said drums.

11. The combination, with a pair of angularly moving towers, a cableway extending between and supported by said towers, and a load handling device on said cableway, of means including a drum for rocking one of said towers, a drum for the other tower, a brake for each of said drums, cables leading from the drum of the first tower to the drum of the second tower, movably supported sheaves carried by each tower for the said cables, normally inoperative means tending to move said sheaves, and connections between each of the sheaves of each tower and the brake for the drum thereof.

12. The combination, with a pair of angularly moving towers, a cableway extending between and supported by said towers and a load handling device on said cableway, means for rocking one of said towers, means including a cable for rocking the other tower from the first tower, a movably supported sheave carried by the first tower for the said cable, normally inoperative means tending

to move said sheave, and a connection between said sheave and the means for rocking the first tower whereby the tower-rocking means is suspended upon the breaking of said cable.

13. The combination, with a pair of angularly moving towers, a cableway extending between and supported by said towers and a load handling device on said cableway, of means for rocking one of said towers, connections between said tower and the other tower for rocking the latter tower in unison with the former, and means for suspending the operation of the tower rocking means when either tower shall have been rocked a predetermined extent from the vertical.

14. The combination, with a pair of angularly moving towers, a cableway extending between and supported by said towers, and a load handling device on said cableway, of connections for rocking one of said towers, connections between said tower and the other tower for rocking the latter tower in unison with the former, and means for suspending the operation of the tower rocking means upon the breaking of the connections for rocking the second tower from the first tower.

15. The combination, with a pair of towers, a cableway extending between and supported by said towers and a load handling device on said cableway, of a rocking support for each tower, a drum supported by each tower, a cable connected to each of said drums, a gear driven by the drum of each tower, a gear segment with which the gear of each tower meshes, and means for driving the drum of each tower.

16. The combination, with a pair of towers, a cableway extending between and supported by said towers and a load handling device on said cableway, of a rocking support for each tower, a shaft supported by each tower, a drum on each shaft, a pair of cables each connected to said drums, a gear on each shaft, a second shaft supported by each tower, means for driving the second shaft of each tower from the first shaft thereof, a gear on the second shaft of each tower, and a gear segment with which the last mentioned gear of each tower meshes.

17. The combination, with a pair of angularly moving towers, a cableway extending between and supported by said towers, and a load handling device on said cableway, of a shaft in each tower, a gear on each shaft, a gear segment with which the gear on each shaft is adapted to mesh, means for driving the shaft of one of said towers, and connections whereby the movement of the last mentioned shaft will be transmitted to the shaft in the other tower.

18. The combination, with a tower, of a rocking support for said tower, means for rocking the said tower about its support, a

brake for such rocking means; abutments on opposite sides of said support, a device carried by said tower and adapted to engage said abutments, and connections between said device and said brake for applying the latter upon the engagement of the said device with either abutment.

19. The combination, with an angularly moving tower, of means for rocking the

same, a brake for such means, and means, 10 operative by the rocking of said tower, for automatically applying said brake when the tower has been rocked to a predetermined extent from the vertical.

In testimony whereof, I hereunto affix my 15 signature.

NORMAN T. HARRINGTON.
